UNDERGARMENT

Arthur M. Thomas, New York, N. Y., assignor to
 Thomas & Marcus, Inc., New York, N. Y., a
 corporation of New York

Application September 20, 1934, Serial No. 744,824

2 Claims. (Cl. 2-78)

This invention relates to underwear, and has for an object to provide an improved construction which may be readily donned or removed, and when in place presents a snug fitting garment.

A further object of the present invention is to provide an improved undergarment for women wherein a complete construction is presented extending from above the breasts to below the 10 crotch, and forming in one combination panties, a shirt body, and a brassière.

A further object, more specifically, is to provide an undergarment of the character mentioned which is removably connected together at 15 the bottom, and which has at the rear near the top elastic means for holding the parts so as to snugly fit the body when in use, but permits a proper distension so that the garment may be passed over the head and downwardly into the 20 proper position.

In the accompanying drawing—

Figure 1 is a front view of an undergarment disclosing an embodiment of the invention;

Figure 2 is a rear view of the garment shown 25 in Figure 1;

Figure 3 is a longitudinal vertical sectional view through Figure 1 on the line 3—3;

Figure 4 is a view similar to the lower part of the structure shown in Figure 3, but with the 30 parts of the crotch strap disconnected;

Figure 5 is a side view of the lower part of the structure shown in Figure 1, with one of the crotch strap sections turned back for better illustrating the construction.

Referring to the accompanying drawing by 35 numerals, 1 indicates the body of the garment, which in a certain sense acts as a shirt, and which merges into panties 2, and also into a brassière 3. The body 1 and also the panties 2 are made preferably from a single piece connected together by the seams 4 along the respective longitudinal edges, said seams extending from the brassière 3 downwardly to the respective leg openings 5 and 6.

It will be observed that the body 1 when lying 45 flat presents at each edge a compound curve with the narrowest part immediately below the brassière 3 and then gradually increasing in width to the upper edge of the respective leg openings 5 and 6. These leg openings are each provided with an elastic band 7 whereby they may snugly fit the leg when the garment is in use. If desired, these bands could be made of some length so as to present tubular leg portions 55 though ordinarily the bands 7 are sufficient.

Arranged centrally of the garment and at the front and back are crotch strap sections 8 and 9 which overlap slightly, as shown in Figure 3, and are disengageably secured together by suitable disengageable fasteners 10. These fasteners may be snaps, buttons or other disengageable fastening means. The sections 8 and 9 are of special construction, each section fitting into a V-shaped opening 11, as shown in Figure 1, and also each section being provided with portions 12 and 13 connected together by a central seam 14. It will be noted that the bands 7 are not tubular until the disengageable fastening means 10 are functioning and, consequently, the bands at the respective ends are stitched to one of the sides of the members 12 and 13. The entire section 8, for instance, is shaped somewhat in the order of a spearhead. The respective seams 14, 15 and 16 act to reinforce and strengthen the garment at this point. It will be noted that both sections 8 and 9 are identical in construction and therefore the description of section 8 is applicable to section 9. When the disengageable fastening means 10 are disengaged or non-functioning the garment will be completely open from the point 17 to point 18 and may be readily passed over the head and shoulders and moved downwardly to a proper position on the body, after which the fasteners 10 are engaged.

In order to cause the upper part of the garment 30 to fit properly and at the same time be able to be passed over the head, there is provided an elastic member 19 which is stitched at points 20 and 21 to the brassière 3 and along the seam 22 to the body 1. When this elastic member is first 35 placed in position the elastic is stretched to almost its fullest extent and stitched in place while so stretched, so that when it is released it will draw the parts together and produce folds or puckles 23.

The brassière 3 is provided with suitable breast 40 pockets 24 and 25 which may be made of the same material as the body 1 or some other material as desired, and secured to the body 1 by a line of stitching 26. Shoulder straps 27 and 28 are connected at spaced points to the elastic 45 19 and to the highest points at the front of the breast pockets, the connection being usually by a suitable form of stitching. Preferably the shoulder straps are inelastic and may be made from ribbon, while the brassière, body and panties 50 may be made from any desired material, for instance, silk, rayon, or some other desirable material, and preferably woven in a manner as to be substantially inelastic.

It will be noted that the elastic bands 7 are stitched in place by suitable lines of stitching 29 and 30 so as to pucker the leg openings of the panties, whereby they may be properly stretched to fit different sized legs. It will be understood that the garment is made from comparatively light material and therefore does not mold the body but conforms itself to the shape of the body and produces a snug fit at the waistline and around the breasts, as well as at the legs.

10 The garment may be worn without a corset or other foundation garment or may be worn over a foundation garment and function to present a pleasing outline as it will automatically conform 15 itself to a corset and to the body of the wearer. When used with a corset or girdle, or when used without a foundation garment the garment embodying the present invention will present a straight line effect whereby a dress placed there- 20 over will present a desirable appearance.

I claim:—

1. An undergarment of the character described, including panties, brassière having rear ends and a shirt section connecting the brassière and the panties, said panties having a crotch strap arranged between the leg openings of the panties, said crotch strap being divided into two parts and disengageably fastened together centrally of the crotch when the garment is in use whereby 25 the parts of the strap may be disengaged and the 30

garment drawn on to the body over the head, said brassière at the rear having an elastic member having one longitudinal edge permanently connected with the shirt portion and the respective ends connected to said rear ends of said brassière, said shirt portion at the elastic section of the brassière being puffed when said elastic member is unstretched whereby the shirt portion at the upper edge and the brassière will resiliently distend when the garment is being placed in position, and the garment will then automatically assume its normal position so as to conform to the body of the person wearing the garment.

2. An undergarment of the character described formed substantially in one piece and presenting 15 at the upper end a brassière, at the center a shirt, and at the bottom panties, said panties having a crotch strap divided into two parts disengageable fastening means for securing the ends of said parts together, and an elastic member forming 20 part of the rear of the brassière to cause the same to fit snugly when in use, said elastic member also having its lower longitudinal edge permanently connected to the upper edge of said shirt portion, 25 the connection with the shirt being such that the shirt portion is puffed to provide a snug fit for the shirt when the elastic member is not under tension.

ARTHUR M. THOMAS. 30
